UNITED STATES PATENT OFFICE.

WILLIAM J. HUFF, OF DECATUR, ILLINOIS.

DESIGN FOR A MEAT-BLOCK.

SPECIFICATION forming part of Design No. 28,815, dated June 7, 1898.

Application filed May 9, 1898. Serial No. 680,221. Term of patent 7 years.

To all whom it may concern:

Be it known that I, WILLIAM J. HUFF, of Decatur, in the county of Macon and State of Illinois, have invented and produced a new 5 and original Design for Meat-Blocks, of which the following is a specification, reference being had to the accompanying drawings, forming part thereof.

Figure 1 is a perspective representation of 10 a block disclosing the configuration of my new design. Fig. 2 is a side elevation. Fig. 3 is an end elevation. Fig. 4 is a plan of the block.

The block is a parallelopipedon having sides 15 of dissimilar area, the broadest of which form the top and bottom of the block.

The vertical corners of the block are chamfered and provided with projecting beaded moldings. The ends have each a set of circular figures disposed in a horizontal line, and 20 the sides have each a set of rectangular figures extending in regular order from one end to the other.

What I claim is—

The design for a meat-block substantially 25 as herein shown and described.

In testimony whereof I sign my name in the presence of two subscribing witnesses.

WILLIAM J. HUFF.

Witnesses:

ANTHONY H. BECK,
L. P. GRAHAM.
